RAILROAD CAR LINK-AND-PIN TYPE
COUPLERWilford E. Fiegler, Hammond, and Hans Lang-
behn, Crown Point, Ind.

Application December 19, 1941, Serial No. 423,598

1 Claim. (Cl. 213—189)

This invention relates to railroad car link-and-pin type couplers such as are used, for instance, to couple ingot cars in a steel mill. More specifically, the invention is concerned with improving the drawheads of these couplers so as to make them more safely used.

A coupler of the type here involved comprises a drawhead having a horizontal surface for the link to rest on when it is inserted in the drawhead, the latter necessarily having clearance for the link resting on its surface to accommodate possible vertical and lateral misalignment with a mating drawhead on another car. The drawhead has a vertical pin opening through this flat surface, in which the pin rides, the pin having a beveled face so that it is downwardly displaceable when the link is forcibly inserted in the drawhead, and being counterweighted so that it is continually urged upwardly. The link rests on its flat surface when it is inserted in the drawhead, with the pin through the pin opening of the link, in an unbalanced condition causing it to droop in a wobbly fashion. Therefore, as the drawhead approaches a mating drawhead for insertion of the link in the latter, it is necessary to manually raise and position the link so that it will properly enter this mating drawhead, this being true in spite of the fact that the drawheads are provided with flaring mouths for aiding in this operation. As is to be expected, many fingers have been lost in carrying out this operation. The purpose of the present invention is to eliminate this unsafe manual positioning of the link.

A specific example of the invention is disclosed by the accompanying drawings, in which:

Fig. 1 is a top view;

Fig. 2 is a vertical longitudinal section;

Fig. 3 is a horizontal longitudinal section; and

Fig. 4 is a section from IV—IV in Fig. 2.

More specifically, these drawings show the drawhead 1 with its flat surface 2 on which the inserted link 3 rests, the vertical pin opening 4 extending through the surface 2 and the pin 5 riding this opening with its end having its beveled face 6 held in the pin opening 7 of the link by reason of the pin 5 being counterpoised through a weighted lever 8 which, incidentally, functions as a handle permitting manual downward movement of the pin 5 from a safe position at the sides of approaching cars. The drawhead has a flared mouth 9 leading to the surface 2, and a buffer surface 9a which engages with that of a mating drawhead during coupling operations and carries the car thrust.

The elements as so far described are those of the prior art coupler of this type. The link 3 fulcrums about the point 10, it being in an unbalanced condition with a majority of its length on the outside of the drawhead beyond this fulcrum point 10. Since, as has been explained, clearance must be provided to accommodate misalignment with another drawhead; that is to say, to permit the pin to wobble somewhat, the outside end of the pin droops to such an extent that it cannot properly enter a mating drawhead in some instances.

According to the present invention the drawhead has a vertically swinging lever 11 fulcrumed by a trunnion mounting 12 to extend backwardly 15 above the flat link resting surface 2, this lever extending over the surface 2 back into the drawhead from its mouth 9 with a vertically swinging portion having a roller 13 displaceable by and engaging with the link 3 when it is forced into the drawhead 1. A coil compression spring 14 works between an end of the lever 11, projecting beyond the roller 13, and the top of the drawhead, the latter being in the form of a removable cover plate 15. The flat surface 2 inwardly of the drawhead adjacent the end of the active pin resting portion, has a downward clean-out opening 16 so that dirt or other obstructions that might enter the drawhead are pushed clear through this clean-out opening so that the drawhead cannot become blocked.

In operation, the link 3 is restrained against drooping by the force of the spring 14 which functions to provide a counterbalancing force, this keeping the link from fulcruming about the point 10. At the same time, it holds the link frictionally down on the flat surface 2 so that it cannot swing laterally with freedom. When the car is in motion, however, the drawhead 3 can work freely to accommodate possible misalignment with the mating drawhead, the spring 14 being sufficiently elastic to permit this action.

When the drawhead is free of the link and is approached by the link, now held in a mating drawhead, the advancing end of the link is guided into the drawhead by the flared mouth 9. At this time the lever is in its downward position. As the pin continues to enter the drawhead it 45 encounters the roller 13 and raises the lever 11, the pin 5 automatically rising and entering the pin opening 7 of the link 3 as soon as registration is attained. Any dirt or other matter that may be in front of the pin is pushed over the surface 50 2 so that it falls through the clean-out opening 55 16.

16, this keeping the drawhead and its working mechanism clear.

Uncoupling is, of course, simple; the lever 8 being manually raised to withdraw the pin 5 so as to free the link 3. It can be appreciated that coupling operations are in a very simple manner made completely automatic and that manual positioning of the link 3, with its attendant danger, is no longer necessary.

We claim:

A railroad car link-and-pin type coupler drawhead having a horizontal flat surface for the link to rest on when inserted in the drawhead, and a vertical pin opening extending through said surface adjacent the mouth of the drawhead with a link-depressible vertical pin riding in this opening and having means for urging it upwardly so it automatically enters the link pin opening when the link is forced into the drawhead, the

5 drawhead being characterized by having a vertically swinging lever fulcrumed above the flat link-resting surface and extending over this surface back into the drawhead from its mouth with a vertically swinging portion provided with a roller displaceable by and engaging with the link when it is forced into the drawhead, and a spring for elastically urging this lever downwardly onto the top of the link when it is inserted in the 10 drawhead with the pin in the link pin opening, the spring having sufficient strength to counter-balance the link against tilting on its flat surface when its other end is not inserted in a 15 mating drawhead, the flat surface inwardly of the drawhead adjacent the end of its active pin resting portion having a downward clean-out opening.
